UNITED STATES PATENT OFFICE

1,925,716

SWINGING BAILED CONNECTER SOCKET

Henry D'Olier, Jr., Bridgeport, Conn.

Original application May 5, 1927, Serial No. 189,058. Divided and this application September 30, 1929. Serial No. 396,213

7 Claims. (Cl. 173—322)

This invention relates to electrical connector socket devices provided with facilities for supporting in assembly a lamp, shade, reflector and the like and for ready connection with and disconnection from overhead supports—the electrical connection being established by a plugging in action as between the cooperating parts of the connector.

The present application is a division of my pending application, Serial Number 189,058, filed May 5, 1927.

My copending application of even date herewith, Serial No. 396,214 is also a divisional application of my pending application, Serial No. 189,058.

The invention may be understood by the following description together with the accompanying drawing in which:

Figure I is a view in elevation of a suspended lighting unit with a connector embodying the invention.

Figure II is a plan view of the lamp supporting parts of the connector ready for installation, the socket being illustrated with a shade-holder fitted therein.

Figure III is a fragmentary detail view in side elevation of the connecting parts shown in Figure I.

Figure IV is a detail view in elevation on a larger scale of the connector members shown in Figure I.

Figure V is a side elevation of the bail shown in Figures I, III and IV.

Figure VI is a view in elevation, partly in section, of the socket member with the parts assembled, with part of a shade holder, and ready to receive the bail and the shade holder.

Figure VII is a modification of the invention wherein the bail engages with the supply wires for supporting the fixture, and Figures VIII and IX are details of the bail and clamping means for engaging the supply wires.

Proceeding now in accordance with the invention, like reference characters refer to similar parts in the respective figures.

In Figure I, the complete lighting fixture is shown in assembled relation, depending by its support from the ceiling, wherein 1, is a glass shade supported by holder 2, which depends for its support in turn by resting upon the top of socket member 3 which is concealed by the holder in Fig. I but shown in Figures IV and VI. Socket 3 is adapted to receive a lamp threadedly, in a conventional manner, or other device. Socket 3 has blades 4—4 projecting upwardly therefrom

and adapted to be received by corresponding apertures in and engage with contacts carried by receptacle 5, the contacts of the latter being connected with supply wires 6. A bail 7 engages in eyes 8 which latter are secured to socket 3. One or both of the eyes may be rotatably secured to the socket 3, and provided with a cushioning spring 9 secured onto eye 8 by nut 10. This arrangement permits of the insertion of one of the extremities of bail 7 into the rotatably mounted eye and allows for a swinging motion of bail 7 into the plane with eyes 8—8 whereupon the extremities of bail may be pressed toward each other, thus permitting ready insertion of the other extremity of the bail into the other eye. The bail may also be inserted in the eyes 8 before the latter are secured into position with socket 3. The upper end of bail 7 may be formed into a loop or eye as at 11 in Figures I, IV and V, for receiving the hook or open ended link 12 carried by chain or overhead support 13 which depends from the ceiling as at 14, 15a being a canopy with hook for engaging the chain. 15—15 are screws for securing shade 1 and reflector 2 in assembled relation. As shown in Figures I, IV and VII, receptacle 5 has a groove 16 on the surface of receptacle 5 to receive bail 7, the purpose of which is that when blades 4—4 of socket 5 are plugged into receptacle 5, the bail 7 being of proper dimension as at —a— Fig. V, may be swung upwardly and snapped into grooves 16.

It will be readily understood that that part of bail 7 depicted at 11 may be formed into a hook for engaging with a link of a chain or the like for supporting the assembled fixture, and affords means whereby ready engagement and disengagement of the fixture may be had instead of the form as shown.

In the modification as shown in VII, VIII and IX the fixture depends for its support upon engagement with the supply wires as follows; bail 7 engages with eyes 8 and snaps into engagement with receptacle 5 in the manner previously pointed out and may be formed with a recess as at 17 to accommodate the supply wires. Bail 7 being provided with a rivet 18 which is received at its opposite end by strap 19, which latter may be readily moved into a position parallel with the upper section of bail 7 and being provided with an opening to receive the same, is passed over threaded stud 20 which latter is thereupon fitted with wing nut 21 by means of which the strap 19 is drawn down on supply wires 6, thus affording frictional engagement therewith by means of 110

which the fixture assembly is supported. The operation is as follows:

Eyes 8 are secured to socket 3, holder 2 is then passed over the socket, blades 4 and eyes 8 projecting through suitable openings in the holder, and a lamp is screwed into the socket. Shade 1 and holder 2 are secured by screws 15 in assembled relation, bail 7 is assembled into eyes 8 and swung away so receptacle 5, which has previously been connected with supply wires 6 depending with chain 13 from the ceiling, may readily be seated upon a socket 3 receiving blades 4, thus establishing the electrical connection with the lamp. Bail 7 is then snapped into grooves 16 and open link 15 or hook 12 receives the bail, thus establishing the mechanical connection for support of the fixture.

To disconnect the socket and its appendages, it remains only to disengage bail 7 from link or hook 12, swinging bail 7 away from receptacle 5 and lowering the fixture which latter movement will of itself disconnect receptacle 5 and socket 3.

While I have shown receptacle 5 provided with grooves 16 and described bail 7 as of such dimension as to seat therein by snapping engagement, this is but a preferred form of my invention as it will be readily understood that the bail may be entirely free from receptacle 5 and the latter be formed without grooves 16 if desired.

In the modified form, the operation is the same as that of the form described above, except that the bail, through strap 17, is caused to engage frictionally with the supply wires and support the fixture thereby instead of engaging with a hook or open link of a depending overhead mechanical support independent of the supply wires. It will be further understood that in the modified form shown, a special or strong covering for the supply wires may be utilized whereby to provide for the strength requisite to support readily the weight of the fixture.

What I claim is:

1. A connector-socket comprising in a unitary structure a connector-member adapted to be connected permanently to electrical conductors; and a socket member provided with means for plugging into said connector member, said connector-socket being further characterized by a swinging bail extending outside of the main connector members for mechanically supporting said unitary connector-socket structure and accessories attached thereto.

2. A connector-socket comprising in a unitary structure a connector-member adapted to be connected permanently to electrical conductors; and a socket member provided with means for plugging into said connector member, said connector-socket being further characterized by a swinging bail extending outside of the main connector members for mechanically supporting said unit-

tary connector-socket structure and accessories attached thereto, said ball being independent of said electric conductors.

3. A connector-socket comprising in a unitary structure a connector-member adapted to be connected permanently to electrical conductors; and a socket member provided with means for plugging into said connector member, said connector-socket being further characterized by means extending outside of the main connector members for mechanically supporting said unitary connector-socket structure and accessories attached thereto, said means comprising a swinging bail.

4. A connector-socket comprising in a unitary structure a connector-member adapted to be connected permanently to electrical conductors; and a socket member provided with means for plugging into said connector member, said connector-socket being further characterized by means extending outside of the main connector members for mechanically supporting said unitary connector-socket structure and accessories attached thereto, said means comprising a swinging bail, mounted pivotally in eyes carried by said socket member.

5. A connector-socket comprising in a unitary structure a connector-member adapted to be connected permanently to electrical conductors; and a socket member provided with means for plugging into said connector member, said connector-socket being further characterized by means extending outside of the main connector members for mechanically supporting said unitary connector-socket structure and accessories attached thereto, said means comprising a bail, mounted pivotally in eyes mounted yieldingly on said socket member.

6. A connector-socket comprising in a unitary structure a connector-member adapted to be connected permanently to electrical conductors; and a socket member provided with means for plugging into said connector member, said connector-socket being further characterized by means extending outside of the main connector members for mechanically supporting said unitary connector-socket structure and accessories attached thereto, said means comprising a bail having a clamp, and a conductor cable adapted to be gripped by said bail clamp, and of sufficient strength to support said socket structure and the accessories attached thereto.

7. A connector-socket comprising a socket member and a receptacle member, one of said members having a notched rib, and a swinging bail carried by said other member and adapted to enter the notched portion of said rib and be retained yieldingly thereby in position to hold said members in assembled position.
